LOCK

Samuel P. Goldberg, Brooklyn, N. Y., assignor to
 Chantrell Lock Corp., a corporation of New
 York

Application June 28, 1928, Serial No. 288,860
 Renewed October 21, 1933

15 Claims. (Cl. 70—92)

The present invention relates to locks and more particularly to mortise locks having a dead bolt operable by a key and/or an inside knob, and a latch bolt operable by the key or a door knob. 5 These locks are suitable for use in doors for office buildings, hotels, apartment houses, commercial buildings, residences, garages and the like.

The present invention contemplates the provision of a lock of this nature wherein it is impossible to move the latch bolt when the dead bolt is in protracted position. In this manner the lock is more difficult to tamper with, for the latch bolt then functions in a way like the dead bolt, and it is necessary to break through both bolts.

A further object of the invention is to provide an improved form of lock construction wherein the dead bolt is held in protracted or retracted position by a tumbler which may take the form of a reciprocatory plate cooperable with a lug or other device on the dead bolt. This tumbler or plate is preferably controllable either by the key or the inside knob to actuate the dead bolt.

In apartment houses, hotels and office buildings it is frequently desirable to provide a master key by which the owner or his agent can open a number of doors in the building. It has been customary to provide such master keys which 30 may actuate both the latch bolt and the dead bolt. The provision of such a master key has been common, notwithstanding the fact that when the space is unoccupied, one can stop the roll back and rely upon the latch bolt for preventing unauthorized entrance, and use the master key to operate the latch bolt.

The possibility of having the master key operate the dead bolt has been found to present many undesirable features such as the possibility 40 of a master key coming into the possession of unauthorized persons and the possibility of the use of the master key to effect an entry when the door has been locked by the key or the inside knob. The possibility of such undesired entry or intrusion by use of the master key has frequently resulted in the installation of a private lock at expense to the tenant and with damage to the door and door casing.

The present invention contemplates the provision of a lock wherein the master key may be used to operate the latch bolt only, and where it is necessary to use the correct key to operate the dead bolt. This makes it impossible to effect entry by means of the master key when the bolt 55 has been locked either by the proper key, or by

the inside knob where one is provided. In this manner the tenant is provided with a lock which can be operated only by one who has the proper key, and it is unnecessary for the tenant to provide an additional lock for which there is no 60 master key. The invention also contemplates the automatic removal of the latch bolt operating mechanism from the range of action of the key operated mechanism when the dead bolt is protracted.

The present invention also contemplates the provision of a lock wherein the dead bolt carries pins normally confined within the dead bolt but adapted to be projected outwardly after the dead bolt passes through the striker plate. According to the preferred construction, these pins are positively moved in and out by mechanical means interconnecting with the pins and the bolt and engaging stationary guides which time and determine the movements of these parts. Accordingly, the position of these parts is always under positive and definite control and in independent of gravity making it impossible for the pins to fall or drop out of place and cause trouble in locking or unlocking.

Other and further objects of the invention will be apparent as the description proceeds.

For convenience in description, all these features will be shown in a lock operated by a cylinder. Many of the novel features of the present invention are, however, capable of embodiment in a lock of the bit key type.

The accompanying drawings show, for purposes of illustrating the present invention, one of the many possible embodiments in which the invention may take form, it being understood that the drawings are illustrative of the invention rather than limiting the same.

In these drawings:

Figure 1 is a side elevational view of the lock with the cover plate removed from the upper part of the lock showing in full lines the dead bolt in retracted position, and showing in dot and dash lines the operation of the latch bolt from the key operated cylinder; either by the master key or the regular key;

Figure 2 is an elevational view showing the position of the dead bolt and latch bolt and interrelated parts in the position assumed when the dead bolt is moved to protracted position, the door knob actuating mechanism for the latch bolt being omitted;

Figure 3 is a view similar to Figure 2 showing the key operated cam moved sufficiently to release the sliding plate or tumbler;

Figure 4 is a sectional view taken on the line 4—4 of Figure 1 looking in the direction of the arrow;

Figure 5 is an elevational view of the back or 5 rear face of the dead bolt, with parts broken away to show interior construction; the lateral pins being withdrawn into the dead bolt;

Figure 6 is a front elevational view of the dead 10 bolt and associated parts in the fully protracted position, the tumbler operating lever being removed; and

Figure 7 is a fragmentary view similar to Figure 2 showing the extent of movement of the cylinder when using the master key and also the 15 inability of either key to operate the latch bolt when the dead bolt is protracted.

The face plate of the lock is indicated at 10. It carries a metal case 11 which is fastened in place by screws 12 passing through lugs 13a on 20 the casing and lugs 13 extending rearwardly from the face plate 10 of the lock. The casing has a side wall 11a, top and bottom walls 11b and 11c, and a rear wall 11d, and is closed by a cover plate 14 fastened in place by screws 15 which pass into 25 threaded bosses 15a carried by the casing. The casing carries posts and the like to support the lock parts, and suitable guides, stops and the like are carried by the casing and cover for cooperation with the movable lock parts. The lock is 30 adapted to be mounted in the door in the usual manner and cooperates with the usual striker plate 10.

The lower part of the lock carries a latch bolt 16 which is adapted to pass through holes 16' and 16'' in the face plate and striker plate in the usual manner. This latch bolt is protracted or urged outwardly by spring 17 surrounding the shank 18 of the latch bolt and the shank is guided by the lugs 19 and 20 carried by the casing. It 40 moves back and forth between lugs 19 and 19'. The latch bolt 16 is adapted to be retracted by the ordinary knob shoe or yoke 21 cooperating in the customary manner with a hub or roll-back 22 adapted to be actuated by the usual knob spindle, 45 not shown. The roll-back 22 is adapted to be locked or released in the usual manner by a reciprocating plunger 23 under the control of buttons 24 and 25 and a lever 26. The latch bolt 16 is provided with forwardly facing shoulders 16a and with a rearwardly facing cam surface 16b for 50 purposes to be described.

The present form of lock is preferably of the cylinder type. A double sleeve key operated cylinder is indicated at 30. This cylinder has two sleeves or barrels, the inner one of which is connected with a double toothed cam member 31 while the outer cylinder is connected to a plate 32 having a single arm 33. The double tooth cam member 31 is adapted to be operated by the guest or owner's key and can be turned through a complete circumference in either direction. The outer sleeve carrying the plate 32 is adapted to be operated by the master key only and is then connected to the inner cylinder to operate it simultaneously. The extent of movement of the outer sleeve is, however, determined by the engagement of the arm 33 with pins 34 and 35 so that it is impossible with a master key to turn the cam member 31 beyond the positions determined by 70 these stop pins. The cylinder is secured in place by the usual screw 36.

The dead bolt 40 is disposed below the cylinder 30 and is protractable and retractable by the cylinder operating through the cam 31. When 75 the dead bolt is retracted as indicated in Figure

1, the end of the dead bolt is flush with the face plate 10 of the lock and the rear end of the bolt is close to the side wall 11d of the case. The dead bolt passes through holes 41 and 41' in the face plate and striker plate and is provided with a slot 42 to receive a guide post 43 carried by the casing 11.

A tumbler operating lever 44 is pivoted on a post 45 extending upwardly from the front face of the dead bolt 40. This tumbler operating lever has two arms 46 and 47. The arm 46 extends along the upper or front face of the dead bolt 40 and is provided with two rearwardly extending cam engaging projections 48 and 49 which pass between the talons 50, 51 and 52 on the dead bolt. The lower arm 47 of the tumbler operating member 44 carries a rearwardly extending pin 53 which passes between the arms 54, and 55 of a bifurcated yoke 56 and into a slot 57 of a sliding locking plate or tumbler 58. The tumbler operating lever 44 is urged upwardly against the talon 52 by means of a spring 59 having its free end anchored behind a lug 60 extending downwardly from the dead bolt 40.

The locking plate 58 is guided for vertical reciprocation by a lug 61 carried by the casing, by one face of the lug 43 and by the rear wall 11d of the casing 11. The upper edge of the tumbler plate 58 is cut back as indicated at 62 and 63 to produce notches adapted to receive the rearwardly projecting lug 64 carried by the dead bolt.

When the dead bolt is in the unlocked or retracted position as indicated in Figure 1, it is possible by use of the proper key to turn the double cam member 31 in a clockwise direction as indicated by the dotted arrow. This will bring the cam face 31a against the cam-receiving projection 48 on the tumbler-operating lever 44. Further movement of the key will press the tumbler operating lever 44 down causing the pin 53 to move the tumbler plate 58 down. This movement of the plate withdraws the notch 63 from the lug 64 so that the dead bolt 40 is free to be protracted or moved toward locked position. During this movement the cam 31a holds the locking tumbler and parts in the lower position until the cam 31b comes against the cam receiving projection 49 on the tumbler operating lever 44. This holds the tumbler in the lower position until the dead bolt is thrown to the extreme left position. The complete path of the cams 31a and 31b is indicated in Figure 2 and it will be clear that after the cam 31b is passed beyond the dead bolt, the spring 59 will force the tumbler operator 44 and the tumbler 58 upwardly causing the notch 62 to receive the lug 64 thereby securing the dead bolt in protracted position and preventing its accidental or unintentional return. During this movement the post 43 and hole 41 have guided the dead bolt 135 for straight line reciprocation.

The employment of two spaced cams 31a and 31b on the cam plate actuated by the key and cooperative cam receiving projections on the lever 44, makes it possible to obtain an increased throw of the dead bolt over what is generally available with the single cam arrangement. The two cams and intervening space together with the arrangement of three talons function similar to a rack and pinion and it is readily possible to provide a throw of an inch in a mortise lock of the usual dimensions.

The dead bolt may also be operated by turning the yoke 56 by a knob 56' or other device cus- 150

tomarily provided on the inside of the door. The turning of this yoke will depress the tumbler 58 to release the bolt and then further movement will actuate the bolt through the post 53 and the branch 47 of the lever 44.

Provision is also made for interconnecting the dead bolt 40 with the latch bolt 16 so that it is impossible to move the latch bolt in when the dead bolt is protracted. To carry out this feature of the invention, the projection 60 on the dead bolt is cooperative with a lever 65 pivoted at 66. The lever is weighted at 67 so that it normally rests on the cam surface 16b of the latch bolt. During the protracting movement of the dead bolt, the face 60' of the lug 60 is brought close to or against the nose of this lever holding it in the full line position of Figures 1 and 2. When the dead bolt is protracted as described, it is impossible to force the latch bolt back by any means whatever for the cross over lever 65 effectively prevents any inward movement of the latch bolt. It is impossible to swing the cross over lever to the right when the locking plate 58 is in a position to lock the dead bolt.

When the dead bolt is in the retracted position it is possible to operate the latch bolt by inserting either the master key or the owner's key into the cylinder. When the owner's key is inserted in the cylinder and turned backward, as indicated in Figure 1, the cam 31b is brought against the nose 70 of a lever 71 pivoted on the stud 72 carried by the casing 11. This will move the lever 70 from the full line position to the dot and dash line position shown in Figure 1. The lever 70 is associated with a second lever 73 pivoted at 74. The free end 75 of the lever 73 engages the shoulder 16a on the latch bolt. Movement of the cam plate 31 in a counterclockwise direction as viewed in Figure 1, it is apparent, will operate the levers 71 and 73 so as to retract the latch bolt 16.

This operation of the latch bolt may be had either by the owner's key or by the master key. When the master key is used the plate 32 is carried around to move the lug 33 from the dotted to the full line position shown in Figure 7 bringing this lug against the stop pin 35. This movement is sufficient to permit the cam 31b to operate the lever 60 for retracting the latch bolt.

In order that the latch bolt retracting mechanism may be in the proper position when the dead bolt is retracted, the dead bolt is provided with a finger or lug 76 which overlies the nose 55 of the lever 71 so as to force this lever to the position indicated. The lever 73 will be held to the full line position of Figure 1 by the spring 18 operating the latch bolt. In order that the lever 70 will be out of the range of the cylinder cam 31, when the dead bolt is in protracted position, provision is made for shifting this lever 70 to the position indicated in Figure 2. In the form shown, this movement is accomplished by a shoulder 77 which engages a fin 78 on the lever 65 70. This shoulder acts on the lever 70 to throw it back to the position shown in Figures 2, 3 and 7 to hold it out of range of the cylinder cams. It is apparent that this lever 71 will be so moved irrespective of whether the dead bolt is actuated by the cylinder 30 or by the knob 56.

According to the preferred construction, the present form of lock is provided with pins bodily carried by the dead bolt which pins are protracted and retracted relative to the dead bolt when the dead bolt is operated. As here shown,

the dead bolt 40 is recessed as indicated at 80. The dead bolt is drilled to receive a pair of pins 81 and 82. Each of these pins has a bifurcated extension 83 to receive a tooth 84 of a pin actuating member 85. These pin actuating members 85 may be alike and are pivoted on pins 86 carried by the dead bolt 40. The pin actuating members 85 are bifurcated as indicated at 87 to receive a rearwardly extending fin 88 carried on a T-shaped sliding member 89. These parts are covered by a plate 90 adapted to slide into an undercut groove provided in the material of the dead bolt, the plate 90 being fastened in place by a screw 91. The T-shaped reciprocatory member 89 is adapted to move back and forth in the recess 80 and has an outwardly projecting stem or guide 92 which carries a pin 93. This slider is adapted to be actuated by a bell crank shaped lever 94 pivoted at 95 to the dead bolt and passing over the pin 93 on the slider 89. The lever 94 is held in place by a portion 96 of the cover plate 90 which overlies it. The free end 97 of the lever 94 is carried adjacent a guide 98 formed in the casing 11.

This guide 98 extends nearly over to the upper lug 13a on the casing and is cut away or beveled slightly as indicated at 99. When the dead bolt is in the retracted position as indicated in Figure 1, the lever 97 is alongside this guide 98 and the other end 100 of the lever is against the upper surface of the lug 43. In this manner the lever 94 is prevented from turning and the pins 81 and 82 are held in the retracted position as indicated in Figure 5.

As the dead bolt is moved outwardly, the 110 guides 98 and 43 hold these locking pins inside the outline of the dead bolt. When the dead bolt is nearly to its extreme movement the lever 100 passes beyond the guide post 43 so as to be free to be moved and this movement is brought about by bringing the nose 101 of the lever 94 against the abutment or stop 13a as indicated in Figure 2. As shown in Figures 2 and 6, this causes a quick clockwise movement of the lever 94 shifting the slider 89 from the position shown in Figure 5 to the position shown in Figure 6 thereby bringing the fin 88 against the opposite side of the bifurcation or slot 87 causing the teeth 84 to act on the pins 81 and 82 to project them outwardly. When these parts have thus 125 been projected outwardly they are held securely by the close fit of the parts.

During the first movement of the retraction of the dead bolt, however, the guide 98 acts on the lever 94 to swing in a counterclockwise direction to accomplish the withdrawal of the pins 81 and 82. The movement of the pins 81 and 82 takes place only when the dead bolt is beyond the striker plate 10'. When projected outwardly they offer a great obstacle to the jamming of the lock.

It is obvious that the invention may be embodied in many forms and constructions, and I wish it to be understood that the particular form shown is but one of the many forms. It is also 140 obvious that certain parts and functions may be omitted if desired. Various modifications and changes being possible, I do not limit myself in any way with respect thereto.

What is claimed is:

1. A lock having a spring protractable latch bolt, mechanism for retracting the latch bolt, a key operated dead bolt mechanism including a tumbler for holding the dead bolt in protracted position, and a movable member adjacent the 150

latch bolt and free to move therewith when the dead bolt is in retracted position, said member being moved to a predetermined position when the dead bolt is protracted, in which position it prevents the retraction of the latch bolt.

2. A lock having a spring protractable latch bolt, mechanism for retracting the latch bolt, a key operated dead bolt mechanism including a tumbler for holding the dead bolt in protracted position, the dead bolt having a lug, a lever pivoted adjacent the latch bolt and having a surface engageable with the latch bolt and an end engageable with the lug on the dead bolt, the lug acting to hold the lever against the latch bolt 15 when the dead bolt is protracted and thereby prevent retraction of the latch bolt.

3. A lock comprising a spring protractable latch bolt, knob operable mechanism for retracting the latch bolt, a dead bolt, a double-sleeve cylinder 20 adapted to receive a master key or an owner's key, the inner sleeve having a tumbler actuating cam for protracting or retracting the dead bolt, and being revolvable only by the owner's key, the outer sleeve and inner sleeve being simultaneously operable only by the master key and then having limited freedom of movement, devices for retracting the latch bolt when the cylinder is operated backward by either the master key or the owner's key with the dead bolt in retracted position, said devices being moved beyond the path 30 of the cam when the dead bolt is protracted, whereby the master key is ineffective.

4. A lock comprising a spring protractable latch bolt, knob operable mechanism for retracting the latch bolt, a dead bolt, a double-sleeve cylinder adapted to receive a master key or an owner's key, the inner sleeve having a tumbler actuating cam for protracting or retracting the dead bolt, and being revolvable only by the owner's key, the outer sleeve and inner sleeve being simultaneously operable only by the master 35 key and then having limited freedom of movement, insufficient for actuating the dead bolt, and devices held in the path of the cam when the dead bolt is retracted and then operable by the cam when moved by either key to retract the latch bolt, said devices being moved beyond the path of the cam when the dead bolt is protracted.

5. A lock comprising a reciprocatory dead bolt, 50 guiding means for the dead bolt, a reciprocatory tumbler having notches to receive a lug on the dead bolt and hold it in protracted or retracted position, a tumbler operating member pivotally mounted on the dead bolt and movable therewith, spring means to hold the tumbler in position to arrest the dead bolt, and a key operated cam for engaging the tumbler operating member to actuate the tumbler and release the bolt, the key operated cam then acting on the dead bolt to protract it or retract it.

6. A lock comprising a reciprocatory dead bolt, guiding means for the dead bolt, a reciprocatory tumbler having notches to receive a lug on the dead bolt and hold it in protracted or retracted 65 position, a tumbler operating member pivotally mounted on the dead bolt and movable therewith, spring means to hold the tumbler in position to arrest the dead bolt, and an inside knob operated yoke engageable with the tumbler operating member to actuate the tumbler and release the bolt, the yoke then acting on the dead bolt to protract it or retract it.

7. A lock comprising a reciprocatory dead bolt, guiding means for the dead bolt, a reciprocatory tumbler having notches to receive a lug on the 75

dead bolt and hold it in protracted or retracted position, a tumbler operating member pivotally mounted on the dead bolt and movable therewith, spring means to hold the tumbler in position to arrest the dead bolt, and a key operated cam and a knob operated yoke both engageable with the tumbler operating member to actuate the tumbler and release the dead bolt, and either of which are then capable of acting on the dead bolt to protract it or retract it.

8. A lock comprising a reciprocatory dead bolt, means for guiding the dead bolt, a reciprocatory tumbler having notches to receive a lug on the dead bolt and hold it in protracted or retracted position, a tumbler operating member pivotally mounted on the dead bolt and movable therewith, the member having extensions passing between talons on the dead bolt, a spring for holding the tumbler in position to arrest the dead bolt, and a double faced key operated cam engageable with one or the other of said extensions to depress the tumbler operating member and tumbler to hold it in position to release the dead bolt, the cam then engaging the talons to shift the dead bolt to the other position and after passing beyond the extensions allowing the spring to restore the tumbler.

9. A lock comprising a reciprocatory dead bolt, means for guiding the dead bolt, a reciprocatory tumbler carried behind the dead bolt and having notches to receive a lug on the dead bolt and hold it in protracted or retracted position, a tumbler operating member pivotally mounted on the front side of the dead bolt and movable therewith, the member having a downwardly extending branch 105 having a pin engageable with a slot in the tumbler, a spring for holding the tumbler in position to arrest the dead bolt and a knob operated yoke pivotally mounted below the bolt and engageable with the pin to actuate the tumbler and shift the 110 dead bolt.

10. A lock comprising a reciprocatory dead bolt, means for guiding the dead bolt, a reciprocatory tumbler carried behind the dead bolt and having notches to receive a lug on the dead bolt and hold it in protracted or retracted position, guides for the tumbler, a tumbler operating member pivotally mounted in the dead bolt and bodily movable therewith, the tumbler being actuated by the movement of the member about its pivot, and 120 key operated means and knob operable means for actuating the tumbler operating member, the tumbler and dead bolt.

11. In a lock, a fixed member, a dead bolt, means to protract or retract the dead bolt, means to 130 arrest it in the position to which it has been moved, laterally movable pins carried by the dead bolt near the free end thereof, means movable with the dead bolt and cooperative with the fixed member for holding the pins confined within the 135 outline of the dead bolt when it is out of the extreme protracted position, and a stationary abutment against which the pin holding means is brought after being carried beyond the guide for projecting the pins beyond the edges of the dead 140 bolt at the dead bolt is moved to extreme protracted position, the means for holding the dead bolt protracted also preventing the forcing of the pins inwardly.

12. In a lock, a dead bolt, means to protract or 145 retract the dead bolt, a lever pivoted on the dead bolt and bodily movable therewith, stationary guides for moving the lever in a predetermined manner as the dead bolt is moved, locking pins normally carried inside the dead bolt, and means 150

actuated by the lever for projecting and withdrawing the pins.

13. In a lock, a dead bolt, means to protract or retract the dead bolt, a tumbler for arresting the dead bolt in either position, a lever pivoted on the dead bolt and bodily movable therewith, stationary guides for moving the lever in a predetermined manner as the dead bolt is moved, locking pins normally carried inside the dead bolt, and means actuated by the lever for projecting and withdrawing the pins, the tumbler when holding the dead bolt in protracted position also holding the lever against a stop whereby outside force applied to the pins is ineffective to move the pins inwardly.

14. In a lock, a dead bolt having a recess, pivot posts in the recess, and laterally extending drillings communicating with the recess, pins reciprocable in the drillings and confined thereby to a

reciprocable movement, pin actuators removably mounted on the pivot posts housed in the recess, a slider separably connected to the pin actuators, and a cover plate holding the slider in operative relation to the pin actuators and holding the pin actuators and slider in the recess.

15. In a lock, a dead bolt, a stationary device adjacent the dead bolt, the bolt having a recess and laterally extending pin guideways communicating with the recess, pins reciprocable in the guideways, pin actuators housed in the recess, a slider connected to the pin actuators, and a slider operating lever pivoted to the dead bolt and the slider, the free end of the lever extending beyond the side of the bolt and being engageable by said stationary devices to reciprocate the pins when the dead bolt is reciprocated.
